Primary Examiner — Mark A Goodwin(74) *Attorney, Agent, or Firm* — FisherBroyles, LLP;
Jason P. Mueller(57) **CLAIM**

The ornamental design for a column splicing bracket assembly, as shown and described.

DESCRIPTION

FIG. 1 is a left-side elevation view of the column splicing bracket assembly;

FIG. 2 is a bottom view thereof;

FIG. 3 is a right-side elevation view thereof;

FIG. 4 is a top view thereof;

FIG. 5 is a rear elevation view thereof;

FIG. 6 is a front elevation view thereof;

FIG. 7 is a front-right, perspective view thereof; and,

FIG. 8 is an expanded view of the front-right, perspective view shown in FIG. 7.
